UNITED STATES PATENT OFFICE.

FRANCES MATTHEW YOUNG, OF DANVILLE, ILLINOIS.

LETTER-CUTTING MACHINE.

1,347,570.

Specification of Letters Patent. Patented July 27, 1920.

Application filed August 15, 1919. Serial No. 317,722.

To all whom it may concern:

Be it known that I, FRANCES M. YOUNG, a citizen of the United States, residing at Danville, in the county of Vermilion and State of Illinois, have invented a new and Improved Letter-Cutting Machine, of which the following is a specification.

My invention is an improved portable machine designed for cutting letters or similar indicia on all flat surfaces of granite, marble, slate, stone or any other material of like nature and which includes a motor driven carborundum wheel constantly in operation as the machine is shifted along in the desired cutting direction by the operator.

Primarily, my invention has for its purpose to provide an improved mechanism of the character stated in which the parts are so assembled and designed whereby the motor and the cutting mechanism actuated thereby may be compactly arranged and conveniently operated.

Another object of my invention is to provide a cutting machine of the character stated in which a simple means is included for adjusting the cutting tool and whereby the said tool may be quickly and positively set by the operator while the cutting element is in action and the machine is being shifted over the surface in which the cuttings are being made.

With other objects in view that will hereinafter appear, my invention embodies the peculiar features of construction and combination of parts, all of which will be hereinafter fully explained, specifically pointed out in the appended claims and illustrated in the accompanying drawings, in which:

Figure 1 is a side elevation of my letter cutting machine.

Fig. 2 is a top plan view thereof.

Fig. 3 is an end elevation of the same looking in the direction of the arrow on Fig. 2.

Fig. 4 is a top plan view of the carriage or base member.

Fig. 5 is a diagrammatic elevation of the release assembly hereinafter specifically referred to.

In my construction of letter cutting machine, the cutting is done by a carborundum wheel driven by a motor that is suitably mounted upon a traveling base or carriage adapted for being conveniently manipulated by the operator, pulling or pushing the same forward as fast as the wheel will cut,

the said carriage being freely movable over the surface of the stone or other material being worked, on rubber faced rollers that are attached to the said base.

The cutting wheel, in my arrangement of the operative parts, is raised or lowered by a peculiar release assembly that co-operates with the cutting wheel mount while the said wheel and the motor are in continuous action, as the operator moves the machine from one position to another.

In carrying out my invention, I provide a base frame or carriage 1, preferably of the shape shown in Fig. 4, to the under side of which are attached a set of rubber covered rollers 2-2, as clearly indicated on Figs. 1 and 4.

4 designates an electric motor which includes a base 5 suitably apertured for receiving the bolts 6 that attach the motor to the said base.

The base 1 has a forwardly extending portion 10 on the outer extremity of which are bolted oppositely disposed vertical standards 7-7 which constitute the end bearings for a cross handle 8 by which the operator can conveniently grip and pull or push the machine over the surface to be cut while the cutting wheel is in operation.

One end 90 of the motor shaft 9 extends laterally of the carriage and constitutes a support for the bearings 11-11 of the upper or yoke-shaped end of an arm 12, which serves as the cutting wheel support.

The cutting wheel 13, see Figs. 1 and 2, is attached to a shaft 31 that journals in the bearings 14-14 on the bifurcated lower end of the said arm 12.

Shaft 31 carries a belt pulley 41 located between the bearings 14-14 over which takes an endless transmission belt 15 that also passes over a pulley 16 on the motor shaft 90 and which is located between the upper bearings 11-11 of the arm 12, as shown.

It is apparent by referring to Figs. 1 and 2 of the drawings that the frame on which the cutter disk or wheel 13 is mounted is swingable in vertical direction relatively to 105 and upon the motor shaft and tends to normally drop into engagement with the surface to be cut.

As is best shown in Fig. 2, the cutter wheel 13 is located laterally of and at some 110 distance from the front end of the carriage and in convenient position for being con-

trolled in its application to the cutting or working condition, by the operator, one of the bearings 14 having an attached forwardly extending handle 18 adapted for being conveniently gripped with one hand of the operator, as he grasps the member 8 with the other hand, during the operation of cutting.

19 designates a rack segment concentric with the axis of the motor shaft and on which the cutter wheel carrying arm is fulcrumed and the said rack segment forms a part of a frame portion 20 that extends laterally inwardly from the yoke-shaped end of the arm 12.

The frame portion 20 includes a rearwardly extending bracket 21 and to the said bracket 21 connects one end of a stout coil spring 22 whose lower end is secured, by one of the bolts 23 presently again referred to, to the base 1.

The purpose of the spring 22 is to constantly swing the arm 12 upwardly, see the arrow ω on Fig. 1, and thereby lift the cutting wheel from the surface to be worked so soon as the operator releases the down pressure on the wheel, which occurs as he shifts the machine from one position to another.

30 The spring 22 and the rack 19 coöperate with a release assembly, the construction of which is shown in detail by Fig. 5 and includes a standard 24 secured by the bolts 23—23 before referred to, to the base 1, and 35 a slot 26 in one of the standards 7 mounted on the forward end of the extension of the base 1 and in line with the standard 24, as is clearly shown in Fig. 3.

40 The release assembly also includes a pawl 45 27 which constitutes a part of a bell crank lever pivotally mounted at 28 to the upper end of the standard 24 and whose lower portion 29 is pivotally connected to a link rod or arm 30, which extends forwardly and pivotally joined with the lower end 32 of a bell crank lever 33 that is pivotally connected as at 34 in the slot 26 in the upper end of the standard 7 and whose upper end extends and terminates with a 50 pusher head 35 located adjacent the handle or grip member 8.

From the foregoing description taken in connection with the drawings, the complete construction, the manner of its use and the 55 advantages of my letter cutting machine will be readily apparent to those familiar with the uses of appliances of like character.

60 The coöoperative arrangement of the parts is such that the operator, while pushing or pulling the machine along the work can, by grasping the handle 8, conveniently press the cutting wheel down to the work under such tension as may be desired, and as the limit of the particular movement or movements of the machine is reached, by reliev-

ing the down pressure on the handle 18 and by then pressing on the pusher head 35, the release assembly operates to pull the pawl 27 away from the rack 19 and thereby allows the spring 22 to come into play and hold the cutting wheel lifted from the surface being worked, as the operator shifts the machine from one position to another, it being understood that as pressure on the head 34 is released, the pawl is restored into engagement with the said rack 19, a spring 36 being connected to the link arm 30 and the standard 24 for facilitating the return of the pawl to engage with the rack.

Another and important function of the spring 22 is, that as the cut is being made and the operator gradually depresses the cutting wheel and as the rack face slips over the pawl, the spring 22 instantly secures the parts (the rack and the pawl) to their newly adjusted position.

What I claim is:

1. In a letter cutting machine, a support, a motor, a cutting tool, means for mounting the said tool toward and from the work, means tending to constantly move the tool from the work, a check device for counteracting the action of the said moving means and a release assembly coöoperative with said check device to release the same and thereby permit the said moving means to freely act.

2. A machine for cutting into hard surfaces such as stone, marble and the like, a carriage, a motor mounted thereon and having a shaft portion extended laterally of the carriage, a cutting tool, means on which the tool is mounted and pivotally sustained on the extended shaft portion to swing vertically to and from the work, means tending to normally swing the said tool carriage to lift the tool from the work, a detent for holding the tool against vertical movement, and other means actuated by the operator as he pushes or pulls the carriage, for releasing the detent to allow the cutting tool to be lifted from the work.

3. A machine for cutting into hard surfaces such as stone, marble and the like, a carriage, a motor mounted thereon and having a shaft portion extended laterally of the carriage, a cutting tool, means on which the tool is mounted and pivotally sustained on the extended shaft portion to swing vertically to and from the work, means tending to normally swing the said tool carriage to lift the tool from the work, a detent for holding the tool against vertical movement and other means actuated by the operator as he pushes or pulls the carriage, for releasing the detent to allow the cutting tool to be lifted from the work, the said means comprising a rack, a pawl pivotally mounted on the carriage, a tension device tending to normally swing the pawl into engagement with the rack, the

said rack and the means on which the tool is mounted moving together and a spring connected with the said cutting tool mount and the carriage tending to normally swing the said mount to lift the tool from the work and a finger actuated means for releasing the pawl from engagement with the rack.

4. In a machine of the character described, the combination of a carriage, a motor mounted thereon, the said carriage having a pair of oppositely disposed standards at one end, a cross member that constitutes a handle for pushing or pulling the carriage mounted at its end on the said opposite standards, the motor shaft including a portion that extends laterally of one side of the carriage, an arm having yoke-shaped upper and lower ends, the upper yoke members thereof constitut-

ing bearings for pivotally engaging the motor shaft extension, one of the upper yoke portions including a segmental rack, a shaft journaled in the lower yoke-shaped end of the arm, the cutting wheel fixedly mounted on the shaft and power transmission connecting the wheel carrying shaft and the motor shaft, tension means tending to normally lift the wheel and its supporting arm from the work, a pawl, a tension device cooperative with the pawl to hold the said pawl and the cutter wheel carrying arm against the tension of the means that lift the cutting wheel and its carrying arm from the work and a finger actuated release for disconnecting the pawl from the rack at times.

FRANCES MATTHEW YOUNG.
